UNITED STATES PATENT OFFICE.

RUSSEL G. WOODWARD, OF WAUKEGAN, ILLINOIS, ASSIGNOR TO UNION SPECIAL SEWING MACHINE CO., OF CHICAGO, ILLINOIS, A CORPORATION OF ILLINOIS.

FEEDING MECHANISM FOR SEWING-MACHINES.

No. 802,789.

Specification of Letters Patent.

Patented Oct. 24, 1905.

Application filed November 9, 1901. Serial No. 81,770.

To all whom it may concern:

Be it known that I, RUSSEL G. WOODWARD, a citizen of the United States, residing at Waukegan, in the county of Lake, State of Illinois, have invented certain new and useful Improvements in Feeding Mechanism for Sewing-Machines, of which the following is a description, reference being had to the accompanying drawings and to the letters and figures of reference marked thereon.

My invention relates to an improvement in sewing-machines, and particularly to a feeding mechanism for machines designed for sewing knit goods, the object of the invention being to provide a feeding device to engage the goods ahead of the needle before the main part of the feed-dog acts, thus crowding the goods up to the needle and preventing puckering after they have been sewed.

I have designed the present invention for application to union special overseaming-machines, such as shown in my application for Letters Patent filed of even date herewith, Serial No. 81,768, or such as shown in an application filed jointly by Lansing Onderdonk and myself on the 9th day of November, 1901, Serial No. 81,772; but it will be understood that it is not desired to so limit the use of the invention, as it may be applied to other machines.

Various devices for accomplishing the same result have been heretofore proposed--as, for example, the provision of the feed-dog with two sets of teeth of varying heights and pitch, the use of separate feed-dogs, one moving in advance of and faster than the other, &c.; but the present invention affords a simple and effective means for accomplishing the same result.

The invention therefore consists in the matters hereinafter described, and referred to in the appended claims.

The invention is illustrated in the accompanying drawings, in which

Figure 1 is a sectional view of so much of a sewing-machine as is necessary to a complete understanding of my invention. Fig. 2 is a view, partly in section, showing the preferred form of feeding mechanism, the various positions of the feed-dog being shown in full and dotted lines. Fig. 3 is a similar view of a modification, showing the original construction devised by me; and Fig. 4 is a detail

view of the connection between the feed-dog and the adjusting-screw. Fig. 5 is a side view, partly in section, showing the corresponding position of the various parts when the needle is at its highest point.

In the drawings the feeding mechanism in general is operated in the manner customary in machines of the union special type and may be understood by referring to Patent No. 299,568. The other parts of the machine are shown in the applications of Onderdonk and myself above referred to.

A is the bed of the machine; B, the driving-shaft; C, the feed-rocker, the parts being actuated in the usual way from a crank-pin on the end of the driving-shaft, the rocking frame, and the cam on the driving-shaft to give the rise and fall to the feed-dog.

As previously stated, in machines of this character for sewing knit goods it is desirable to crowd the goods toward the needle before the stitching takes place to prevent puckering after the stitches have been passed through the fabric, and an inclined feed-dog F is therefore used, so arranged that as the upward movement takes place that part of it ahead of the needle will catch the goods first. To vary the inclination, the construction shown in Fig. 2 is preferably provided and may be described as follows: The block 1, to which the feed-dog F is secured, is pivoted on a screw-bolt 2, attached to the rocking arm D, and said block is provided near its lower end with an internal ball-shaped socket 3, with a slot 4 opening downwardly. Fitting in this socket is a ball 5 on the end of a rod 6, which rod 6 projects to the rear of the machine and is provided with a suitable milled knob 7. The rod 6 is screw-threaded for a portion of its length, as shown at 8, and passes through a screw-threaded abutment 9 on the rocking arm D, so that by manipulation of the knob the feed-dog-supporting block may be swung on its pivot to vary the inclination of the feed-dog with respect to the line of the cloth-plate.

In Figs. 3 and 4 is illustrated a modification of the manner of securing the rod 6 to the feed-dog block. In this arrangement the block is provided with a downward-slotted extension 10 and having the ribs 11 formed therein, the rod 6 being slotted to receive these ribs.

It will be noticed that the feed-dog may be

easily adjusted and without removing the cloth or throat plate and that said adjustment may be effected without stopping the machine.

Various minor modifications and changes in 5 the construction of the parts may be made without departing from the spirit of my invention.

Having thus described my invention, what I claim as new, and desire to secure by Letters 10 Patent, is—

1. In a sewing-machine having a cloth-plate, and a feeding mechanism including a feed-dog, the cloth-plate surface and the entire feeding- 15 surface of the feed-dog, being relatively inclined to each other from front to rear in the direction of the feed, and the feeding-surface of the feed-dog engaging the fabric both in front and in rear of the needle across its entire upper face; substantially as described.

2. In a sewing-machine having a cloth-plate, and a feeding mechanism including a feed-dog, the cloth-plate surface and the entire feeding- 20 surface of the feed-dog, being relatively inclined to each other from front to rear in the direction of the feed, and the feeding-surface of the feed-dog engaging the fabric both in front and in rear of the needle across its entire upper face; substantially as described.

3. In a sewing-machine having a cloth-plate, and a feeding mechanism including a feed-dog, the cloth-plate surface and the entire feeding- 25 surface of the feed-dog, being relatively inclined to each other from front to rear in the direction of the feed, and the feeding-surface of the feed-dog engaging the fabric both in front and in rear of the needle across its entire upper face; substantially as described.

4. In a sewing-machine having a cloth-plate, and a feeding mechanism including a feed-dog, the cloth-plate surface and the entire feeding- 30 surface of the feed-dog, being relatively inclined to each other from front to rear in the direction of the feed, and the feeding-surface of the feed-dog engaging the fabric both in front and in rear of the needle across its entire upper face; substantially as described.

5. In a sewing-machine having a cloth-plate, and a feeding mechanism, including a feed-dog, whose feeding-surface from front to rear is inclined with respect to the cloth-plate sur- 35 face and engages the fabric both in front and in rear of the needle across its entire upper face, with means for operating the same, whereby the relatively high portion of the feed-dog will engage the fabric first and im-

40 part to it a forward movement before the stitching takes place, the fabric after stitching being fed forward by the feed, substantially as described.

6. A feeding mechanism for sewing- 45 machines, including a feed-dog arranged with its entire upper feeding-surface inclined from front to rear in the direction of the feed with respect to the cloth-plate surface, and engaging the fabric both in front and in rear of the

50 needle with means for operating the same, whereby the high portion of the feed-dog will engage the fabric first and impart to it a forward movement before the stitching takes place, the fabric after stitching being fed for-

55 ward by the feed, and means for adjusting the inclination of the feed-dog; substantially as described.

7. A feeding mechanism for sewing- 60 machines, including a feed-dog having its feed- ing-surface in front of the needle in a higher plane than the feeding-surface in the rear

thereof, the entire feeding-surface being inclined with respect to the cloth-plate and in the direction of the feed whereby as the upward and forward movement of the feed takes 65 place, that part of it ahead of the needle will catch and feed the goods first crowding the goods up to the needle; substantially as described.

8. A feeding mechanism for sewing- 70 machines, including a feed-dog pivoted upon an axis transverse to the direction of its length, with means for imparting the feeding movements to the feed-dog, and means for adjusting the feed-dog on its pivot to vary the incli- 75 nation of the feed-dog with respect to the cloth-plate surface; substantially as described.

9. A feeding mechanism for sewing- 80 machines, including a feed-dog, a rocking arm upon which the same is pivoted to swing upon an axis transverse to the direction of its length, and a rod for adjusting the same, freely connected to said feed-dog, and means for manipulating the rod; substantially as described. 85

10. A feed mechanism for sewing-ma- 90 chines, including a pivoted block to which the feed-dog is secured, having a recessed slot, a rod having a head fitting the recess in said slot, and having a screw-threaded portion engag- 95 ing the threads of a suitable abutment; sub- stantially as described.

11. A feeding mechanism for sewing-ma- 100 chines, including a feed-dog pivoted to its supporting rocking arm, said supporting 95 rocking arm being provided with a screw-threaded projection, and a rod provided with screw-threads engaging the screw-threads of the projection, and freely connected to said feed-dog, and means for manipulating the rod; 100 substantially as described.

12. A feeding mechanism for sewing- 105 machines, including a feed-rocker, and a feed- dog pivoted to its supporting rocking arm, a rod for adjusting the same freely connected 105 to said feed-dog and passing through an opening in the feed-rocker, and means for manipulating the rod; substantially as described.

13. In a feeding mechanism for sewing- 110 machines, including a pivoted member to which the feed-dog is connected, said pivoted member being provided with a slotted lower ex- tension, and an adjusting-rod having a head fitting in said slotted lower extension; sub- 110 substantially as described.

In testimony whereof I affix my signature in presence of two witnesses.

RUSSEL G. WOODWARD.
